UNITED STATES PATENT OFFICE

SØREN WISTOFT, OF FREDERIKSBERG, DENMARK

RELEASING MECHANISM FOR AUTOMATIC VENDING MACHINES

Application filed June 24, 1929. Serial No. 373,354.

The invention relates to a releasing mechanism for automatic vending machines, which can distinguish between coins with flange and coins without flange and are of the type which with this object in view have a pair of feelers with beaks turned towards one another, between which the coins inserted into the automatic machine will fall down.

The releasing mechanism in question is essentially characterized in this that the said feelers are formed of flat springs secured outside to the side walls of a coin passage, the lower end of which springs are bent towards one another and are situated beneath the said coin passage and form the feeler beaks, and in this that beneath, but a little aside of the opening between these beaks there is arranged a stop member against which a coin inserted into the machine will strike and which has the effect that the coin, if it has no flange, rolls so that it falls down at the one side of a partition to be thereafter in a suitable manner led out of the machine, whereas the coin, if it has a flange, rolls and moves thus, guided both by the beaks of the feelers gripping inside of the flange and by the said stop member, that it effects an opening of the feelers (bending of these in a direction from one another) whereupon it falls down along the other side of the said partition to thereafter in the usual manner release the locking of the opening member of the machine.

In the accompanying drawings

Fig. 1 is the part of the said releasing mechanism, necessary for the comprehension of the invention, in front elevation and

Fig. 2 the same seen from the left side in Fig. 1.

Through a usual, not shown coin chute the coin inserted into the machine rolls down and into a coin passage 2. This is located between a pair of stationary plates 3 the upper parts 3¹ of which are bent so that the coin passage has the shape of a funnel, while the

plates are otherwise vertical. At the sides (to the right and the left, Fig. 1) the coin passage 2 is limited by the inner edge of sheet metal strips 1 and 5, which are fixed between the plates 3. The sheet metal strip 1 to the left (Fig. 1) has below an inwardly extending lug 11. This strip, the inner edge of which from the said lug upwards is vertical along the greater part of the length of the strip and then extends obliquely to the left, does not reach quite down into line with the lower edge of the plates 3. The strip 5 to the right consists at its inner edge essentially of two vertical portions 4 and 4¹ with an intermediate horizontal shoulder 4², which is so determined that the distance from the vertical inside edge of the strip 1 to the portion 4 of the inner edge of the strip 5 is equal to or almost equal to the distance from the end of the lug 11 of the former strip to the portion 4¹ of the strip 5, and equal to or almost equal to the vertical distance between the shoulder 4² and the upper edge of the lug 11. By this means the coin passage 2 is L shaped.

The strip 5 reaches down a distance below the lower edge of the plates 3, and its lower end is angle-shaped in such a manner that it here forms an arm 6 which extends under a part of the lower opening of the coin passage 2. On the arm 6 there is pivotally suspended a pawl 7 having in cross section the shape like an inverted U, so that it can be readily turned up from its normal position, as shown in the drawings which the pawl will again assume due to its gravity when it is no more under an action for turning it into the said direction. The lower edges of the pawl are surfaces 8 which extend obliquely upwards in a direction towards the free end of the pawl.

9 are the two aforementioned flat springs, forming the coin feelers of the mechanism, and which are each fitted opposite one another to the outside of the plates 3. Each spring 9 is at its upper end fixed to the respective plate 3 by means of a screw 10 from

which the spring extends vertically downwards and normally bears against the outer side of the plate 3. The lower portions of the spring 9 are curved inwardly towards one another, there being provided small outcrops 14 in the bottoms of the plates 3 for the said portions to pass through, and the side edges of the curved portion of each spring are thus convergent in a direction towards the lower end of the spring so that the latter will terminate in an almost pointed beak 12.

When the springs (feelers) 9 are in their normal position, the beaks 12 are beneath the coin passage 2 at a short distance from same, and are located at a distance from one another substantially equal to the thickness of a coin, for which the machine is intended, within its flange. The outer end of the pawl 7 is a little to the side of the opening between the beaks 12, and it may here be mentioned that the upper surface of the pawl has a quite slight incline in a direction towards the common vertical mean plane of the springs (feelers) 9. The free length of these and therewith their stiffness may be adjusted by means of adjusting arms 15, one such arm for each spring 9. The adjusting arm 15 of a spring 9 is arranged as a single-armed lever on a screw 16 which is screwed into the respective plate 3, and on tightening this screw the arm 15 may be caused to bear against the spring 9 at some place lower than the screw 10 by means of which the upper end of the spring is fixed to the said plate.

13 is a stationary partition arranged at a suitable place in the machine casing.

The operation is as follows:

Whether a coin with flange or a coin without flange after insertion into the machine falls from the coin chute down into the coin passage 2, it will owing to the above mentioned form of the latter strike against the lug 11 and be thereby partly stopped before it falls further down between the feeler beaks 12, so that the coin will always reach these beaks at a comparatively small velocity.

Let it be first assumed that a coin for which the machine is intended (a coin with flange) is inserted. During its passage through the coin passage 2 the coin will with its flange strike against the feeler beaks 12. By its kinetic energy the coin will hereby bend the feelers (the springs) 9 so far in a direction away from one another, that the flange of the coin can pass between the beaks 12, so that these will grip the coin within the flange. Almost simultaneously the coin will strike against the pawl 7, whereby its downward movement will be arrested. But the coin will now move to the left (Fig. 1) on the pawl, guided by the feeler beaks 12 within the flange, until it is no more supported by the pawl. At this movement the centre of gravity of the coin will be obliquely below to the left of the place where the

beaks 12 grip the coin close within the flange of the same, and the consequence thereof will be that the coin will now suddenly move under the action of its gravity downwards with the inner edges of its flange sliding on the said beaks and will simultaneously therewith swing counter-clockwise, during which swinging movement the coin will be acting from below against the oblique under edges 8 of the pawl 7, turn the pawl clockwise. Thereby the coin will with a certain kinetic energy strike against the two beaks 12 at the moment its centre of gravity is vertically beneath the space between the beaks.

By this action the feelers (springs) 9 will be bent so far that they will release the coin, which latter will fall down vertically, whereby it is caused to fall down to the right of the wall 13, whence it may in any suitable way be guided on to release the locking of the opening member of the machine. As soon as the coin has fallen, the pawl 7 will due to its gravity swing back into its normal position.

If instead of a coin with flange, a coin without flange is inserted into the machine, such a coin will after having struck against the pawl 7 roll to the left on the same without being affected by the beaks 12. The coin will in this manner roll directly off the pawl in the said direction and fall down so that it will fall to the left of the partition 13, to thereafter be led out of the machine.

Some details may be altered without departing from the scope of the invention.

I claim:

1. A releasing mechanism for vending machines including a coin chute, which can distinguish between flanged and flangeless coins introduced into the chute, comprising a pair of feelers consisting of flat springs having their upper ends fixed to the opposite sides of the chute, said feelers having upon their lower ends beaks directed towards each other, a partition below the beaks, a stop member disposed below the beaks and in offset relation with respect thereto, said stop member and beaks cooperating to direct a flanged coin to one side of the partition, said stop member also serving to direct a flangeless coin to the opposite side of the partition, as and for the purpose set forth.

2. A device as claimed in claim 1, wherein the stop member is in the nature of a pawl swingable upwardly under the influence of a flanged coin which when rolling on the pawl and guided by the beaks will assume a position unsupported by the pawl and will by gravity move downwardly and swing in a direction toward the pawl.

3. A device as claimed in claim 1 wherein the stop member is of inverted U-shape in cross section and is pivotally connected, the under edge of the stop having an oblique surface on which a coin with a flange acts during swinging of the stop member.

4. A device as claimed in claim 1 wherein
the coin chute is provided with a shoulder
against which the coins strike and are momen-
tarily arrested before they fall between the
5 beaks, whereby the coins will reach the beaks
at a relatively small velocity.

5. A device as claimed in claim 1, wherein
the said opposite sides of the chute have arms
fixed thereto and adjustable to bear against
10 the springs constituting the feelers.

In testimony whereof I affix my signature.
SOREN WISTOFT.
